United States Patent Office

Des. 212,364
Patented Oct. 8, 1968

212,364

TRANSFORMER ENCLOSURE

Buell Moore, Houston, Tex., assignor to Esquire, Inc.,
New York, N.Y., a corporation of Delaware

Filed Mar. 4, 1968, Ser. No. 10,844

Term of patent 14 years

(Cl. D26—15)

Fig. 1

Fig. 2

Fig. 3

FIGURE 1 is a top perspective view of a transformer enclosure showing my design;

FIGURE 2 is a side view from the opposite side, of the transformer enclosure shown in FIGURE 1; and

FIGURE 3 is a top view of the transformer enclosure shown in FIGS. 1 and 2.

The undisclosed side is flat and plain.

I claim:

The ornamental design for a transformer enclosure, as shown and described.
